UNITED STATES PATENT OFFICE.

WILLIAM B. FULTON, OF MIDDLETOWN, OHIO.

VAPOR-CIRCULATING SYSTEM.

1,286,988.

Specification of Letters Patent. Patented Dec. 10, 1915.

Application filed January 10, 1918. Serial No. 211,259.

To all whom it may concern:

Be it known that I, WILLIAM B. FULTON, a citizen of the United States, residing at Middletown, Butler county, Ohio, have invented certain new and useful Improvements in Vapor-Circulating Systems, of which the following is a specification.

Circumstances arise in which it is desirable to bring about the circulation of vapor in a system in which one portion of the vapor requires to be dealt with at a given pressure while another portion or other portions of the vapor require to be dealt with at a lower pressure or even at a partial vacuum. For instance, assume a group of paper machine driers heated by steam passed into them at a given pressure to bring about a given intensity of drying, and assume a second group of the driers, for the performance of a lower intensity of drying, this second group of driers being heated by steam received from the first group at a lower pressure, or possibly at a partial vacuum. It is the purpose of my system to facilitate the movement of the vapors and water of condensation in such a general system involving a plurality of pressures, two pressures as in the example just cited, or a greater number of pressures.

My invention will be readily understood from the following description taken in connection with the accompanying drawings in which:

Figure 1 is a front elevation of an organization exemplifying my invention adapted for use in connection with two groups of paper machine driers, parts appearing in vertical section in the plane of line *a* of Figs. 3 and 4:

Fig. 2 a side elevation of the automatic valve-mechanism, a portion appearing in vertical section in the plane of line *b* of Figs. 1 and 4:

Fig. 3 a side elevation of the receiver and its near accessories, parts appearing in vertical section in the plane of lines *c*, *d* and *e* of Fig. 1 and line *e* of Fig. 4: and

Fig. 4 a plan of a portion of the apparatus, a horizontal section appearing in the plane of line *f* of Figs. 1 and 3.

In the drawings:

1, indicates a receiver:

2, a pipe connected with the receiver and adapted to convey steam and water of con-

densation thereto from the high pressure element of the system, such, for instance, as the high pressure group of paper machine driers:

3, a pipe connected with the receiver for conveying steam from the receiver to a lower-pressure element of the system, such, for instance, as a low-pressure group of paper machine driers:

4, a baffle disposed within the receiver to prevent the direct flow of entrained water to the outlet 3:

5, a pump of any suitable character, preferably of sufficient capacity to handle the water of condensation from the receiver and from the low-pressure element of the system and to maintain a partial vacuum in the low-pressure element:

6, a pipe connected with the suction side of the pump and adapted to lead from the discharge of the second element of the general system as, for instance, the low-pressure group of paper machine driers.

7, a pipe placing the suction side of the pump in communication with the base of the receiver:

8, an automatic valve disposed in this pipe 7 and adapted, as hereinafter explained, to control flow from the receiver to the pump:

9, a check-valve in pipe 7, opening toward the pump:

10, a lever pivoted to the body of automatic valve 8 and connected with its valve-stem:

11, a weight adjustable along the lever and tending to urge the automatic valve to normally closed position:

12, a water-vessel hung upon the lever, in opposition to weight 11, and disposed at a vertical height corresponding, in a general way, with the level of water to be controlled in the receiver:

13, the normal level of water in the receiver and also, as will be later seen, in the water-vessel:

14, a flexible pipe, as a hose, connecting the upper portion of the water-vessel with the receiver at a point above the normal water level in the receiver:

15, a similar flexible pipe connecting the base of the water vessel with a point in the receiver below the normal water level therein:

16, a water-gage, on the receiver:

17, various drain-pipes connected with the system:

18, a pipe connecting the suction side of 5 the pump with the base of the receiver, independent of pipe 7:

19, a check-valve in pipe 6, opening toward the pump:

20, an air-valve or cock discharging from 10 the receiver: and 21, cold-water pipe leading to pipe 7.

The various pipes of the system are provided with hand valves where needed or useful. The pump may be a pump in fact 15 or its place may be taken by any suitable suction device, such as an ejector or a siphon-pipe. The automatic valve may be of any usual construction of balanced stop-valves.

20 Assume that the system is empty; that the valves controlling the drain-pipes 17 are closed; that automatic valve 8 is closed; that the valve in pipe 18 is closed so that that pipe is out of service; that all other valves 25 are open, except the check-valves; that pipe 2 is connected with the outlet of the high-pressure element of the system being dealt with; that pipe 3 is connected with the inlet of the low-pressure element of the system 30 being dealt with; that pipe 6 is connected with the outlet of the low-pressure element of the system being dealt with; and that the pump is working.

High-pressure steam, which is supplied to 35 the high-pressure element of the system, performs its duty therein and becomes reduced in temperature and pressure; the steam at the reduced pressure, together with the water of condensation, goes through pipe 40 2 to the receiver and fills the receiver; valve 20 is to be closed after the displaced air has become discharged from the receiver; the water of condensation settles in the base of the receiver; steam goes from the receiver 45 through pipe 3 to the low-pressure element of the system and acts therein in performing its heating office at a lower-temperature and pressure than in the first element of the system; baffle 4 prevents entrained water 50 entering the receiver by pipe 2 from going directly to outlet 3; the steam together with the water of condensation, goes from the low-pressure element of the system through pipe 6 toward the pump; cold water from 55 pipe 21 condenses such steam as there may be; the pump discharges this water of condensation and may produce a partial vacuum in the low-pressure element.

Water of condensation will eventually act 60 cumulate in the base of the receiver and reach the water-level 13; at this time water will have reached the same level in vessel 12 through flexible pipe 15; at this time the weight of the vessel with its contained water 65 will just counterbalance the weight 11, valve

8 remaining closed; further accumulation of water raises the level in the receiver and in the water-vessel and increases the weight of the latter; the preponderance of weight of the water-vessel over the weight 11 causes a slight opening of valve 8; the pump now receives and discharges this excess water; the pump is at this time pulling on the receiver and on the low-pressure element of the system; the withdrawal of the excess water 70 causes a restoration of water level in the receiver and in the water-vessel, and valve 8 closes; the pump now pulls only on the low-pressure element of the system; and the pump may thus, under the control of the 75 automatic valve, maintain a constant water-level in the receiver, without interfering with the action of the pump on the low-pressure element, and without danger of the vacuum in the low-pressure element being broken down by the pressure from the receiver.

I find in practice that the water is withdrawn from the receiver in minute quantities, a mere film, so to speak, and that the movements of the automatic valve mechanism are barely perceptible and that the water level in the receiver becomes controlled with great nicety.

It has thus far been assumed that the 95 pump was dealing with a single receiver, but it is obvious that suction pipe 7 of the pump might be connected with any desired number of receivers, etc., within the capacity of the pump. If the automatic valve should 100 become disordered in any way, then the hand valves may be so operated as to cut the automatic valve off from the receiver and place the receiver in communication with the pump through the medium of by-pass pipe 105 18, it being understood, of course, that the valve controlling the by-pass valve will be set with extreme nicety or else opened only on occasions. The valves in the drain-pipes 110 17 permit of the drainage of the entire apparatus, even the water-vessels 12 draining through the receiver.

I claim:—

1. In a vapor circulating system, the combination of a receiver, a steam connection to the upper portion thereof adapted to lead steam from the high pressure element of a system to be dealt with, a steam connection from the receiver adapted to convey steam from the upper portion of the receiver to a low pressure element of the system being dealt with, a suction device, a pipe connection adapted to convey steam from such low pressure element of the system to the suction device, a pipe connecting the suction device with the lower portion of the receiver, a valve in the last-mentioned pipe between the receiver and the pipe leading from the low pressure element of the system, and automatic means exterior to the receiver for con- 115 120 125 130

trolling said valve by changes of level of water in the receiver, combined substantially as set forth.

2. A structure as specified in claim 1 in combination with a valved bypass pipe connected with the receiver and with the suction device between it and said automatic valve, substantially as set forth.

3. A structure as specified in claim 1 in combination with a water-pipe connected 10 with the inlet of the suction device, substantially as set forth.
